UNITED STATES PATENT OFFICE.

PHILIP BRASHER, OF NEW YORK, N. Y.

PROTECTING OBJECTS FROM WAVE ACTION.

1,391,992.

Specification of Letters Patent. Patented Sept. 27, 1921.

Application filed September 11, 1920. Serial No. 409,682.

To all whom it may concern:

Be it known that I, PHILIP BRASHER, a citizen of the United States, and a resident of the city of New York, borough of Manhattan, in the county and State of New York, have invented Improvements in Protecting Objects from Wave Action, of which the following is a full, clear, and exact description.

10 This invention relates to improved means for protecting objects from wave action, and more particularly for discharging air upwardly through the water for breaking up the waves, an object of the invention being to provide improved means for discharging from the apparatus sand or foreign matter which may accumulate therein.

15 A further object is to improve upon the construction disclosed in Patent Number 20 843926, granted to me February 12, 1907, for protecting objects from wave action.

25 With these and other objects in view the invention consists in certain novel features of construction, and combinations and arrangements of parts, as will be more fully hereinafter described and pointed out in the claims.

In the accompanying drawings—

30 Figure 1 is a vertical sectional elevation or profile, showing means embodying my invention applied to the protection of a bulkhead.

Fig. 2 is an enlarged view in transverse section through the air discharge pipe.

35 Fig. 3 is a broken view in longitudinal section through the air discharge pipe.

40 1 represents an air discharge pipe which is submerged in the water 2 and mounted on any suitable support 3 and located at any 45 desired distance from the bulkhead or bank 4, and adapted to discharge air upwardly through perforations 5 in the top of the air pipe 1, so that said air will bubble up through the water and serve to break up the waves.

45 6 represents an air pump or other source of compressed air supply which is connected by a supply pipe 7 with the air discharge pipe 1, so as to supply the air to said discharge pipe, the control of the air being provided by means of a valve or cock 8 in the supply pipe 7.

50 It is possible that in the use of the device sand may drift into and through the 55 perforations 5 in the top of discharge pipe 1, ultimately so filling the said air pipe as

to interfere with the discharge of the air, and it is the purpose of my invention to provide means which overcome any such difficulty.

With this idea in view, I provide in the bottom of the air discharge pipe 1 an air pipe 9 of relatively small diameter having relatively small perforations 10 in its bottom, said pipe 9 resting on the bottom of the pipe 1. The pipe 9 has a closed end 11, which closure may constitute an ordinary plug as indicated, or the pipe may be closed in any approved manner, and the end of discharge pipe 1 is also closed, a cap 12 being indicated for the purpose.

With the inlet end of the pipe 1 is preferably connected by an elbow 13 with the supply pipe 7 and the relatively small pipe 9, which constitutes a clean-out pipe, has its inlet end extending through the elbow and any desired distance up into the air supply pipe 7, as shown at 14. This pipe is extended into the air supply pipe a distance which is far enough away from the discharge pipe 1 to prevent any possibility of the inlet end of said pipe 9 becoming clogged with the sand or other foreign matter.

The operation is as follows: During the operation of the device, when air is being discharged through the perforations 5, no sand or foreign matter can enter said pipe 1, but while the apparatus is idle, it is possible that sand may drift in through the perforations 5 and ultimately fill the pipe 1. If this is true, as soon as the air is turned on, it, due to the fact that it cannot pass through the pipe 1, will enter the inlet end of the pipe 9 and escape through the perforations 10 in the bottom of said pipe 9 and whirl upwardly through the pipe 1 and out of the perforations 5, thus carrying with it the sand which may have accumulated in the pipe 1.

The perforations 10 of pipe 9 are located in the bottom of said pipe 9 and against the lower wall of the pipe 1. In such position the sand cannot drift into the said pipe 9, but the air which is under considerable pressure, will find its way around both sides of the pipe 9 and, in fact, said pipe 9 being laid loosely in the pipe 1, will be more or less elevated by the action of the air so that there will be a free escape of air upwardly and through the perforations 5 until the pipe 1 is cleared when the air will flow directly into the pipe 1 from the supply pipe 7.

It is, of course, obvious that various modifications might be resorted to in the general structure which would carry out the same general idea of an additional or auxiliary air supply pipe which would function to blow the sand out of the main air discharge pipe, and while I have illustrated what I believe to be a preferred embodiment of this idea, it is obvious that various changes might be made in the general form and arrangement of the parts described without departing from the invention, and hence I do not limit myself to the precise details set forth, but consider myself at liberty to make such changes and alterations as fairly fall within the spirit and scope of the appended claims.

I claim:

1. An apparatus of the character stated, comprising a pair of perforated air discharge pipes, one pipe of appreciably smaller diameter than the other and located within the other.

2. An apparatus of the character described, comprising an air discharge pipe having air outlets in its top, and a perfo-

rated air pipe of smaller diameter located in the discharge pipe.

3. An apparatus of the character described, comprising an air discharge pipe 30 having air outlets in its top, and an air pipe of smaller diameter located in the discharge pipe and having perforations in its bottom.

4. An apparatus of the character described, comprising an air discharge pipe 35 having air outlets in its top, and an air pipe of smaller diameter located in the discharge pipe and having perforations in its bottom, said perforated portion of the smaller pipe normally resting upon the bottom of the 40 discharge pipe.

5. An apparatus of the character described, comprising an air discharge pipe having perforations in its top, an air supply pipe communicating with said discharge 45 pipe, an air pipe of smaller diameter than the discharge pipe resting upon the bottom of the discharge pipe and having perforations in its lower portion, and said smaller pipe having an inlet end projecting into the 50 air supply pipe.

PHILIP BRASHER.
